[57] CLAIM

The ornamental design for a auto safety distance sensor, as shown and described.

DESCRIPTION

FIG. 1 is a diagrammatic perspective view of the auto safety distance sensor;

FIG. 2 is a front elevational view thereof;

FIG. 3 is a left side elevational view thereof;

FIG. 4 is a right side elevational view thereof;

FIG. 5 is a rear elevational view of the auto safety distance sensor;

FIG. 6 is a top plan view thereof; and,

FIG. 7 is a bottom plan view thereof.
